Primary Examiner — T. Chase Nelson*Assistant Examiner* — Eric Goodman*(74) Attorney, Agent, or Firm* — Thomas C. Sailta(57) **CLAIM**

The ornamental design for a slotted catheter securement device, as shown.

DESCRIPTION

FIG. 1 is a perspective view of the invention.

FIG. 2 is a left side view.

FIG. 3 is a front view.

FIG. 4 is a right side view.

FIG. 5 is a top view.

FIG. 6 is a bottom view; and,

FIG. 7 is a back view.
